UNITED STATES PATENT OFFICE.

ANDREW CRAIK, OF WILLIAMSPORT, PENNSYLVANIA.

SECTIONAL STEAM-BOILER.

SPECIFICATION forming part of Letters Patent No. 334,568, dated January 19, 1886.
Application filed May 11, 1885. Serial No. 165,073. (No model.)

To all whom it may concern:

Be it known that I, ANDREW CRAIK, of Williamsport, in the county of Lycoming and State of Pennsylvania, have invented certain 5 new and useful Improvements in Sectional Steam-Boilers, of which the following is a specification.

My invention relates to that class of steam-generators known as "sectional boilers;" and 10 it consists in a novel construction of the same, as hereinafter set forth.

In the drawings, Figure 1 is a vertical central section of my improved boiler; and Fig. 2 is a horizontal section of the same on the 15 line $\alpha\alpha$, Fig. 1.

The object of my invention is, primarily, to increase the heating-surface and cause the flames to remain for a long time in contact with the generator, while rendering the construction 20 cheap and strong and permitting repairs to be easily made; and to this end I construct the boiler as shown in the drawings, in which—

A indicates the base of the boiler, composed 25 of sections $a b c$. The section a forms the base proper of the boiler, on which it rests, and on which the section b is placed. Section b is provided with an outwardly-extended ledge or flange, d , which rests upon the top of section a , lugs or hangers e on its lower inner face, which support the grate B , and an annular water-chamber, f , as clearly shown in 30 Fig. 1. The upper edge of section b is formed with a ledge, upon which rests the section c , the latter extending upward and outward, as shown in Fig. 1, and provided at its upper 35 end with a seat or socket for the jacket or casing C . This jacket or casing C extends upward quite a distance, and is furnished at its top with a conical cap, D , from which the 40 smoke and products of combustion are carried off by a pipe. The lower edge of the cap D is formed with an inwardly-extending flange, g , from which depends a circular jacket, h , extending 45 downward nearly to the section b , as shown in Fig. 1. The flange g may be cast with the cap D , or it may be sustained by and rest upon lugs cast or bolted to the body c ; and it is likewise apparent that the depending 50 jacket h may be either cast with and form a part of the flange g , or be bolted thereto. I

prefer, however, to cast the parts separate and bolt them together, as it not only renders easier the casting of the several parts, but also enables them to be assembled and put in place with more ease. The section b is furnished with hollow standards or legs i , which extend upward and support the series of water-chambers E , as shown in Fig. 1. These chambers E are of the peculiar form shown in 55 Figs. 1 and 2—that is to say, they are flat and hollow, provided with a central supply and discharge orifice, j , and with vertical heat flues or passages k in their laterally-extending wings or arms, as clearly shown in Figs. 1 and 60 2, resembling in form the figure 8. The number of the chambers may be varied as desired, and although I have shown eight I do not confine myself to the number.

The upper and lower central passages, j , are 65 threaded to receive a short connecting pipe or thimble, l , which is threaded at both ends and screws into the adjacent faces of the chambers E , as shown in Fig. 1, thereby connecting the chambers firmly together, and at the same time serving to conduct the water from 70 one to another.

It will be seen, upon reference to the drawings, that the chambers E are placed at an angle with the chambers above and below, 75 thus serving to intercept and heat much more thoroughly than if they were placed directly one over another. The upper chamber E is connected to a steam chamber or dome, F , (shown in Fig. 1,) which I prefer to make of 80 spherical form.

A pipe, m , passes from the upper end of the steam-dome F to an engine, or to any other place to which it is desired to convey the steam for use. Extending outward through the casing are two pipes, n , which are tapped into 85 two of the generating-chambers, and connected at their outer ends to a water-gage, G , as shown in Fig. 1.

In order to feed fuel to the furnace or grate, 90 I provide a door, H , (shown in Fig. 1,) the position of which may be changed as desired. I prefer, however, to place it high enough to utilize the space between jackets C and h as a magazine for fuel.

The smoke and gases passing up between the jacket or casing C and the annular inter-

nal jacket, *h*, escape into the inner chamber through holes or perforations *n* in the jacket *h*, about midway of its length above the door *H*. A pipe, *o*, enters the bottom chamber *E*, and serves as the feed or supply pipe for the boiler.

I prefer to extend the section *c* upward on the interior of the casing *C*, a considerable distance, as shown in Fig. 1, in order to prevent said casing, which is much lighter, from burning out.

As the flames and gases arise, they pass around and through the passages *k* of the chambers *E*, and heat the water therein, the heat and flames being deflected as they pass upward by the chambers *E*. This particular manner of mounting the chambers *E*—that is to say, the alternating position—tends to greatly increase the generating capacity of the boiler.

The advantages of the 8 form over the cylindrical generators heretofore used are apparent. They are much lighter, and consequently easier to handle and put in place, are smaller and easier to cast, are cheaper, and, finally, they permit the gases and heat to pass up on all sides, and also through the vertical flues in their ends, thereby utilizing to the greatest possible degree all the heat.

The entire weight of the chambers comes upon the lower section, *a*, and it will be seen that by the manner of connecting the chambers, as herein shown, I dispense with all tie-bolts, such as are usually employed. These tie-bolts passing through the connecting-pipes tend to reduce the available water-space and enhance the cost of construction. Under my construction I have an uninterrupted water-space through the pipes *l* from top to bottom.

As shown clearly in Fig. 2, the water is confined in a passage of 8 shape, substantially, the heat passing up on all sides of the water and through the flues *k* in the ends of the generator.

The thimbles may be threaded alike at both ends or right and left, in which latter case the

chamber will be turned to screw it upon a thimble previously screwed into the chamber 45 below.

Two or more pipes, *p*, connect the bottom annular water-chamber *f* with two of the upper chambers *E*, in order that there may be a perfect circulation of water through the chambers *E*.

Having thus described my invention, what I claim is—

1. In a sectional steam-boiler, the combination, with a casing or body and a fire-pot, of a series of chambers, *E*, of 8 form, substantially, and provided with a central water-outlet, *j*, and with vertical heat-flues *k* in its ends.

2. In a sectional steam-boiler constructed substantially as herein shown and described, the base *A*, consisting of sections *a b c*, the section *b* provided with upright hollow legs *i*, which support the chambers *E*, as set forth.

3. In a sectional steam-boiler substantially such as shown, the base *A*, consisting of the sections *a b c*, section *c* supporting the outer casing, and section *b* supporting the grate and the generating-chambers and resting upon section *a*, as set forth.

4. In a sectional steam-boiler, the combination, with base *A*, grate *B*, casing *C*, top *D*, and chambers *E*, of flange *g* and depending jacket *h*, as and for the purpose set forth.

5. In combination with generating-chambers *E* and fire-pot *B*, annular jackets *Ch*, enclosing the chambers *E* and forming a fuel-magazine, substantially as described and shown.

6. In a sectional steam-boiler substantially such as shown and described, the combination of the chambers *E* and *f* and the pipes *p*, connecting the same, as shown.

ANDREW CRAIK.
